DISTRIBUTOR MEMBER FOR STOKERS

Paul A. Ketchpel, West Englewood, N. J., assignor to The Standard Stoker Company, Incorporated, a corporation of Delaware

Application August 18, 1932. Serial No. 629,256

9 Claims. (Cl. 110—101)

The invention relates to the distributor member for stokers of the type wherein a conduit communicates endwise with the firing opening of a boiler firebox. As the invention appertains to the distributor member and its associated parts, only so much of the remainder of the stoker mechanism is shown as is necessary to indicate the relation of the parts. The distributor member or distributor head as it is known in the trade, is exposed to the intense heat of the firebox. Because of this it is frequently replaced under some conditions of service.

It is the main purpose of the invention to provide an improved and novel construction of the stoker conduit and the distributor member whereby the latter can be easily and readily removed from its position. Other objects of the invention reside in the specific form of the parts and in the particular fastening means employed 20 to hold the distributor member in place.

On the drawing,

Fig. 1 is a detail vertical section through the upright wall of a boiler firebox showing the device of the invention applied thereto in similar 25 section;

Fig. 2 is a transverse section taken on the irregular section line 2—2 of Fig. 1;

Fig. 3 is a fragmentary vertical sectional view on the line 3—3 of Fig. 1; and

Fig. 4 is a fragmentary transverse section on the line 4—4 of Fig. 2.

Referring to the drawing, there is shown at 10 a portion of an upstanding wall of a boiler firebox having a firing opening 11 therein to which fuel is advanced by the screw 12 housed within the inclined stoker conduit 13 which opens endwise into the firing opening. The mouth portion 14 of the conduit extends across the lower portion of the firing opening. Any preferred construction may be employed to attach the conduit to the wall 10 to maintain the conduit mouth portion in communication with the firing opening. In cross section the mouth portion 14 of the conduit is substantially rectangular in 45 shape and the lower portion of the conduit is substantially circular in cross sectional form as best shown in Figures 1 and 3. The bottom of the mouth portion 14 is open between the sidewalls 14a, 14b, and forward of the ledge 15. A distributor member or head 16 having a flat upper surface is detachably disposed as will presently appear in the open bottom of the mouth portion 14 to form in effect a floor portion for the delivery end of the conduit. It will be observed 55 that the distributor member extends beyond the

conduit mouth portion into the firing opening to a point adjacent or beyond the inside surface of the firebox wall 10. The plate portion 16a of the distributor head disposed within the firebox may be formed integral with the head, but preferably, it is constructed as a separable part as herein illustrated. As the manner in which the plate is attached to the head forms no part of this invention it will not be described.

A plurality of vertically spaced horizontal rows 65 of jet openings as at 17 extend across the upright face 18 of the distributor member. These jet openings communicate with one or more chambers 19 formed within the distributor member. Steam or any other suitable pressure fluid 70 is supplied to the chambers through the laterally directed passages 20 positioned outside the firebox. Fuel advanced by the screw 12 is moved over the distributor member 16 into the zone of action of the pressure fluid blasts discharging 75 from the jet openings 17, which blasts serve to project the fuel across the plate 16a over the firebed of the firebox. Adjustable deflector vanes 21 constitute continuations of the sidewalls of the mouth portion of the conduit within the 80 firing opening 11 and they may be set to vary the distribution of the fuel.

An improved construction is provided for supporting and attaching the distributor member 16 to the stoker conduit 13. For this purpose, oppositely disposed lugs 22, 22a extend inwardly from the lower marginal edges of the sidewalls 14a, 14b, of the mouth portion 14 of the stoker conduit, and likewise spaced lugs 23 extend forwardly from the ledge 15. These lugs contact 90 the underside of the chambered portion of the distributor member 16, in effect constituting a seat for the same in the open bottom of the mouth portion 14. The distributor member is held in the seat formed by the aforesaid lugs by oppositely disposed pins 24, 24a projecting through the sidewalls 14a, 14b, above and contacting the upper surface of the end portion of the distributor member adjacent the lugs. These pins 100 are threaded in the sidewalls 14a, 14b and can be inserted or removed by applying a wrench or the like to the hexagonal head of each pin. The axis of the pins is disposed above the upper flat face of the distributor member a distance 105 slightly less than one half the diameter of the pins. With this location and by tapering the inner ends of the pins it will be understood that when inserting the pins they gradually press down against the distributor member and insure a firm 110

attachment of the same to the conduit regardless of variations in the size of the parts.

Longitudinal movement of the distributor member 16 toward the wall 10 is prevented by engagement of the upstanding lugs 25, 25a against the side of the tapered ends of the pins 24, 24a, remote from the aforesaid wall. The lugs 25, 25a and the threaded pins because of their location in the corners formed at the junction of the circular and rectangular portions of the stoker conduit do not interfere with the movement of the screw 12 nor with the fuel being advanced thereby. It is preferred that all of the lugs herefore named and that the threaded pins should be disposed as illustrated without the firebox where they will not be subjected to the heat of the fire and where the pins are readily accessible.

When the distributor member 16 becomes cracked, burned, warped or for any other reason 20 is not fit for continual use it may be readily removed by withdrawing the threaded pins 24, 24a. This detachability of the parts not only reduces the cost of replacement, but permits the interchange of parts with the minimum of labor 25 or delay.

The construction disclosed and described represents the preferred and commercially used 30 form of the invention, but various changes of detail may be made without departing from the scope of the invention.

I claim:

1. In a stoker, the combination of a conduit, a distributor member constituting the floor portion of the delivery end of the conduit, a seat 35 formed in said conduit for receiving said member, and oppositely disposed pins having their inner ends tapered and threaded through opposite sidewalls of the conduit and extending therein above but contacting said member for detachably securing the same on said seat.

2. In a stoker, the combination of a conduit, a distributor member constituting the floor portion of the delivery end of the conduit, a seat 45 formed in said conduit for receiving said member, and oppositely disposed pins having their inner ends tapered and threaded through opposite sidewalls of the conduit and extending therein above but contacting said member for detachably securing the same on said seat, and 50 upstanding lugs on said member contacting the sides of the pins remote from the delivery end of the conduit.

3. In a stoker, the combination of a conduit, a distributor member constituting the floor portion 55 of the delivery end of the conduit, a seat formed in said conduit for receiving said member, a pin element threaded through a sidewall of the conduit and extending therein above but contacting said member for detachably securing the same on said seat, and a lug element on said member contacting the side of said pin element remote from the delivery end of the conduit, the contacting surface of one of said elements being tapered to insure a rigid connection between the distributor member and the conduit when the pin element is threaded in position.

4. In a stoker, the combination of a conduit, a detachable floor member for said conduit, a seat formed with the conduit for receiving said member, a pin element threaded through a sidewall of the conduit and extending therein above but contacting said member for detachably securing the same on said seat, and a lug element on said member contacting the side of said pin element remote from the delivery end of the con-

duit, the contacting surface of one of said elements being tapered to insure a rigid connection between the distributor member and the conduit when the pin element is threaded in position.

5. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, a pin element threaded in a sidewall of the rectangular portion of the conduit adjacent the junction between the said conduit portions and projecting through said wall into the conduit at a point above but contacting said member, and a lug element on said member contacting the side of said pin element remote from the delivery end of the conduit, the contacting surface of one of said elements being tapered to insure a rigid connection between the distributor member and the conduit when the pin element is threaded in position.

6. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, and a pin 100 threaded in a sidewall of the rectangular portion of the conduit adjacent the junction between the said conduit portions and projecting through said wall into the conduit at a point above but contacting said member, the axis of said pin being above the distributor member a distance less than one half the diameter of the pin and the end of the pin tapered to gradually contact the distributor member as the pin is threaded in position.

7. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, a pin threaded in a sidewall of the rectangular portion of the conduit adjacent the junction between the said conduit portions and projecting through said wall into the conduit at a point above but contacting said member, the axis of said pin being above the distributor member a distance less than one half the diameter of the pin and the end of the pin tapered to gradually contact the distributor 110 member as the pin is threaded in position.

8. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, a pin threaded in a sidewall of the rectangular portion of the conduit adjacent the junction between the said conduit portions and projecting through said wall into the conduit at a point above but contacting said member, the axis of said pin being above the distributor member a distance less than one half the diameter of the pin and the end of the pin tapered to gradually contact the distributor 120 member as the pin is threaded in position.

9. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, a pin threaded in a sidewall of the rectangular portion of the conduit adjacent the junction between the said conduit portions and projecting through said wall into the conduit at a point above but contacting said member, the axis of said pin being above the distributor member a distance less than one half the diameter of the pin and the end of the pin tapered to gradually contact the distributor 130 member as the pin is threaded in position.

10. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, a pin threaded in a sidewall of the rectangular portion of the conduit adjacent the junction between the said conduit portions and projecting through said wall into the conduit at a point above but contacting said member, the axis of said pin being above the distributor member a distance less than one half the diameter of the pin and the end of the pin tapered to gradually contact the distributor 140 member as the pin is threaded in position.

11. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, a pin threaded in a sidewall of the rectangular portion of the conduit adjacent the junction between the said conduit portions and projecting through said wall into the conduit at a point above but contacting said member, the axis of said pin being above the distributor member a distance less than one half the diameter of the pin and the end of the pin tapered to gradually contact the distributor 150 member as the pin is threaded in position.

- member as the pin is threaded in position, and a projection on said member engaging the side of the tapered portion of said pin remote from the discharge end of the conduit. 9. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, and oppositely disposed pins threaded in opposite side walls of the rectangular portion of the conduit adjacent the junction between the said conduit portions and projecting through said walls into the conduit at points above but contacting said member, the inner ends of said pins being tapered. 8. In a stoker, the combination of a conduit having a substantially circular receiving end portion and a substantially rectangularly shaped delivery end portion, the latter having an open bottom, lugs extending from the walls of the said rectangular portion inwardly of the open bottom constituting a seat disposed below the plane of the bottom of the circular portion of the conduit, a distributor member loosely disposed on said seat constituting a floor for the rectangular portion of the conduit forming a continuation of the circular portion of the conduit, said member extending from the junction of said portions of the conduit to the delivery end thereof, oppositely disposed pins threaded in opposite side walls of the rectangular portion of the conduit adjacent the junction between the said conduit portions and projecting through said walls into the conduit at a point above but contacting said member, the inner ends of said pins being tapered, and upstanding projections on said member engaging the sides of said pins remote from the delivery end of the conduit.
